MINERAL SEPARATING APPARATUS

Jean E. Courcq, Los Angeles, Calif.

Application April 17, 1939, Serial No. 268,297

8 Claims. (Cl. 209—468)

This invention relates generally to mineral separators of the type commonly known as dry separators, and more particularly to that class of dry separator and separating process which operate by mechanical agitation assisted by air currents.

Dry separators of the class referred to may be designed for separation of flakes and nuggets of gold or platinum from gravel as found in placer deposits, or for concentration of the valuable particles of crushed or reduced ore. The present invention has been specifically designed with the problems incident to separation of gold from placer deposits chiefly in view, and will therefore be hereinafter described in that particular connection, but without implied limitation thereto.

In prior dry separators employing mechanical agitation, or mechanical agitation combined with air currents, the gravel containing the gold is placed on a shaker or riffle board of some sort, usually inclined, and is regularly shaken or reciprocated. The gold particles being heavy, tend to sink through the mass of material, and are collected by pockets or riffles in the shaker or riffle board. Air currents are often used as an aid to separation, being frequently directed against and through screen members of which the bottom of the shaker or riffle board is composed.

The general object of the present invention is to provide an improved dry separator of simple construction which has comparatively large capacity combined with a relatively high percentage of recovery of the values present.

The separator provided by the present invention embodies, in its preferred form, a shaker member mounted for vibratory movement along an inclined direction line, and having an inclined surface or surfaces over which the incoming material is passed. The shaker is moved alternately slowly downwardly of the incline, and then quickly back, being brought to a sudden stop on the up or back stroke. This novel action has the effect, on each up or back stroke, of throwing the particles of gold, which are relatively heavy, backwardly through the gravel, i. e., in a direction up the incline. To aid this action, the inclined surfaces of the shaker are formed with upwardly or rearwardly directed jagged formations or teeth. Because of their density, the gold particles sink through the gravel and encounter these teeth, which prevent them from sliding further down the incline, but function to throw them up the incline on each up stroke of

the shaker. Cooperating with this mechanical action are certain air currents, which act to separate the lighter material from the heavy, tend to move the entire mass of gravel down the incline, and orient the gold particles for most effective travel back through the gravel and up the incline. The gold so induced to travel up the jagged or toothed inclined surface or surfaces is collected from time to time from the head end of said surfaces. The action of the separator is particularly effective and efficient, and recovery of as high as 95% of the contained gold is commonly achieved.

The invention will be more fully understood from the following detailed description of a present preferred embodiment thereof, reference for this purpose being had to the accompanying drawings, in which:

Fig. 1 is a longitudinal vertical section through a machine in accordance with the invention;

Fig. 2 is a section taken on line 2—2 of Fig. 1;

Fig. 3 is an enlargement of a portion of Fig. 1, being a vertical longitudinal section through the shaker frame;

Fig. 4 is a section taken on line 4—4 of Fig. 1;

Fig. 5 is an end elevation of the shaker frame, as viewed from the left in Fig. 3;

Fig. 6 is a view taken as indicated by arrows 6—6 of Fig. 1, the feed hopper being removed;

Fig. 7 is a detail enlargement taken from Fig. 1;

Fig. 8 is an enlargement of a portion of Fig. 1; and

Fig. 9 is an enlargement of a portion of Fig. 6, with parts broken away.

The machine illustrated in the drawings is provided with a suitable frame work, indicated generally by the numeral 10, which supports an inclined chute 11. The latter comprises parallel inclined side members 12, and a bottom 13 abutting against and secured to the lower edges of members 12. The side members 12 are secured to upright members 14 and 15 of frame 10, in the manner indicated. Mounted on one of members 12, near its upper end, and on a parallel member 12a that extends between frame member 14a and a cross-member 14b, are bearings 16 for a horizontal transversely extending drive shaft 17, said shaft carrying a suitable fly-wheel 18, a cam 19, and a crank disk 20, here shown as integral with cam 19. Shaft 17 may be driven in any suitable manner, as for example by a hand crank; in the present instance, fly-wheel 18 is indicated as provided with a crank handle 21,

by which the fly-wheel and shaft may be rotated.

The gravel containing the mineral particles to be recovered, such as gold flakes and nuggets, is deposited within a hopper 25, which is mounted on supports 26 secured to and extending from the sides 12 of chute 11. The hopper is preferably provided at the bottom with a gate 27 by means of which the rate of feed of gravel into the machine may be regulated. The bottom of hopper 25 is connected by means of flexible conduit or connection 28 with the upper end portion of a shaker frame generally designated at 30, the latter being disposed within chute 11, and means later to be described being provided for reciprocating it in a direction longitudinally of said chute.

Shaker frame 30 comprises an upper end wall 31, side walls 32, and lower end member 33. Members 31 and 32 are inwardly flanged at their lower edges, as indicated at 34 and 35, respectively, and an angle member 36 extends between side 32 below the aforementioned member 33, having a flange 37 in the plane of flanges 34 and 35. Flanges 35 slidably engage strips 40 extending longitudinally of chute 11 and secured in the angles formed between sides and bottom of the chute (see Fig. 4). Flanges 34 and 37 slidably engage cross strips 41 and 42, respectively, which are secured to chute bottom 13. The described flanges on the bottom of the shaker frame are adapted to slide on these members 40, 41 and 42 in a direction longitudinally of the chute. Air pressure is supplied to the shaker frame by way of the air space or chamber 45 defined by strips 40, 41 and 42 and the chute bottom. In order to hold the air pressure within this space 45, the upper sides of strips 40, 41 and 42 are faced with strips 46 of some suitable material such as leather, which will permit free sliding action of the shaker frame but will at the same time afford a sufficiently good seal against escape of air that the necessary pressure may be held.

To reduce sliding friction to a minimum, the shaker frame is preferably provided with some suitable anti-friction supports which will prevent the full weight of the frame and contained material from becoming imposed on the leather strips. As here typically shown, the shaker frame has at each end a pair of laterally projecting perforated supports 47, formed of hardened steel, which are slideable on short, hardened rails 48 mounted on chute sides 12 (see Figs. 6 and 9).

The shaker frame is provided a short distance below the upper edges of sides 32, with a top wall 50 which extends from rear wall 31 to a point spaced somewhat toward the opposite end of the frame, being provided at that point with an inwardly turned flange portion 51. A removable, flanged cover member 52 fits between said flange portion 51 and the aforementioned end member 33 of the frame, and extends the full distance between the sides 32 of the frame, as illustrated in Figs. 3 and 4. This cover member 52 is adapted to be secured in position as by means of screws 54 passing through its flanges and the sides 32 of the shaker frame. The purpose of this cover 52 is to confine certain later described air currents that flow through the shaker frame, so that their velocity will be kept up and their action on the materials will be at a maximum.

The material enters shaker frame 30 by way of a long slot 60 in top member 50, falling

initially upon a wall 61 which is parallel to top 50 and has its side edges abutting side walls 32. This member 61 has a flange 62 adjacent end wall 31, which may be secured to wall 31 by suitable means such as screws 63. Member 61 is parallel to top 50 for a distance forwardly from end wall 31, and then has a somewhat downwardly inclined portion 60a, terminating in a flange 60b turned at right angles to the top 50 of the frame. The material deposited on member 61 by way of aperture 60 slides down incline 60a and over flange 60b.

Below member 61, the shaker frame is provided with a series of jagged, slightly inclined step like surfaces 65, 66 and 67, which are arranged parallel to one another, and over which the material passes in succession. These surfaces or steps 65, 66 and 67 extend the full distance between side members 32, being secured at their edges to said members 32 in any suitable manner. The last step 67 is furnished with a flange 68 abutting angle member 36, and the material discharged from said step 67 passes out of the shaker frame by way of the outlet 69 between angle member 36 and the outwardly flaring lower portion 68a of the previously mentioned end member 33.

In the present illustrative embodiment of the machine, chute 11 is disposed at an angle of approximately 30° with horizontal, so that shaker frame 30 is likewise disposed at an angle of substantially 30° with horizontal. Steps 65, 66 and 67 are arranged at such angle that when the shaker frame is in the machine they will have a downward inclination in the same direction, but at a much less angle; in a present illustrative embodiment, this angle is approximately 4° with horizontal. An angle substantially greater than 4° brings about too great a tendency for the gold particles to travel downwardly by reason of gravity, while if the steps are too near horizontal, the benefit of gravity in moving the gravel down the incline is undesirably diminished. However, while I have specified 4° as being approximately correct for best results, there is some available leeway on both sides of this angle within which efficient performance is obtained.

Attention is directed to the fact that the jagged steps 65, 66 and 67 are made up of a series of pointed teeth 70, somewhat in the nature of ratchet teeth, which are directed against the direction of gravel flow through the shaker frame, or in other words, up the incline. These teeth, which are parallel and extend the full width of the steps between side members 32, act to catch the heavier particles of material (gold or other heavy values) that settle down within the gravel passing thereover, holding said material against travel down the general incline, and tending to move that material in an upward direction when the shaker frame is moved upwardly of the chute. This action will be described in more detail at a later point in the specification.

As will be seen from an inspection of Fig. 4, the upper end of first step 65 is just at or below the flange 60b on member 61. Extending upwardly from the upper end of this step 65 is a wall member 71, furnished at its upper end with an upstanding flange 72, the upper end of which is spaced a short distance below wall member 61 to provide a constricted air passage therebetween. Pressure air from the space 45 between the bottom of the shaker frame and chute bottom 13, and which is developed as by a bellows

system B, hereinafter to be more particularly described, passes between the upper end of this flange 72 and wall 61, and is discharged into the space inside the shaker frame between the lower edge of flange 60b and the wall member 71 at the top of jagged step 65. This air current has several functions, as will later be explained.

At the bottom of step 65 is a flange 75 which is turned downwardly, at right angle to step 65, the lower end of this flange being located just above the upper end portion of step 66. A flange 76 extending from the upper end of step 66, parallel to and spaced behind flange 75, affords an air passage from space 45 over the upper edge of flange 76, downwardly between said flanges, and outwardly below the lower edge of flange 75 across the teeth of step 66. Step 66 has at its lower end a down turned flange 78 similar to the flange 75 of step 65. I preferably incorporate in the series of jagged or toothed steps a pocket adapted to catch or collect particles of gold of such large size that they might not be retained by the teeth 70, and in the present embodiment of the invention, such a pocket, indicated generally by numeral 80, intervenes between steps 66 and 67. Thus the material discharged from the lower end of step 66 and falling over flange 78 is caught by a somewhat downwardly inclined wall 81, which merges at the bottom into a channel or pocket 82. The upper end of this wall 81 has a flange 83 spaced back of and disposed parallel to flange 78, thereby forming an air passage similar to that described at the head of the preceding step 66.

The wall member forming channel or pocket 82 has a section 82a extending downwardly from said channel, approximately parallel to steps 65, 66 and 67, and terminates in a flange 84 similar and parallel to the flanges 75 and 78 at the lower edges of steps 65 and 66, the lower edge of this flange 84 being located above the upper end portion of the lowermost step 67. The upper edge of step 67 has an upturned flange 85 spaced back of and disposed parallel to flange 84, forming an air passage from space 45 between said flanges and discharging below the lower edge of flange 84 in a direction downwardly of step 67.

The pressure air may be delivered into space 45 in any suitable or convenient manner. I here show a simple and convenient system for delivering a suitable supply of air by means of the simple bellows and accumulator system designated generally at B. Preferably, a double bellows system is employed, the two members of which pump air alternately, so that a substantially continuous flow of air is developed. In the specific and preferred arrangement here shown, two bellows 86 and 87 are mounted on the underside of a horizontal supporting means 88, mounted in any suitable manner on legs 14 and 15, the two bellows being disposed in opposed relation, with their pivots 86a and 87a adjacent to one another, in the manner clearly illustrated in Fig. 1. A connecting rod 90 is connected at its upper end to crank disk 20 and pivotally connected at its lower end to a bellows operating bar 91, which is connected at 92 and at 93 with the movable sides of bellows 86 and 87, respectively. When connecting rod 90 is reciprocated by crank disk 20, bellows operating bar 91 is caused to move in such a way as to work bellows 86 and 87 simultaneously but in opposed directions; thus, bellows 86 is closed as bellows 87 is opened, and vice versa, so that the two deliver air alternately.

Bellows 86 and 87 are diagrammatically indi-

cated as provided with usual intake valves at 86b and 87b, respectively, and with usual discharge valves 86c and 87c, respectively, the latter both discharging into a flexible tank or accumulator 95. These valves are of a conventional type and need not be detailed. Flexible tank or accumulator 95 is made up of typical bellows construction, having a flexible, corrugated side wall 95a, together with bottom 95b mounted on support

10 99 and a top 95c which is free to move in a vertical direction depending upon the pressure of the contained air. A flexible connection 96 connects flexible tank 95 with the space 45 between chute bottom 13 and the shaker member 39. 15 Thus the upper end of this flexible connection 96, which may also be of bellows construction, is fitted around an aperture 97 in chute bottom 13 leading to space 45. The lower end of flexible connection 96 is connected to the upper side 20 95c of flexible tank 95, communicated with the interior of tank 95 by way of a suitable opening 95d in member 95c.

For the purpose of distributing the air pressure uniformly within chamber or air space 45, a 25 perforated deflector plate 98 is preferably mounted in said chamber over aperture 97 (Figs. 1 and 2), the air being delivered both through the perforations 98a in said deflector plate and also by way of the openings 99 under the edges of said plate. Air deflector plate 98 is supported at a suitable elevation above trough bottom wall 13 by means of suitable feet or supports 98b located at its four corners.

A detachable connection is made between 35 flexible tube 28 and the aperture 60 in the upper wall 50 of shaker frame 30, and as here shown, this connection comprises simply an apertured block 100 mounted on the lower end of flexible tube 28 and engageable with wall 50 around aperture 60, this block having dovetail shaped edges 101 adapted to be received within a dovetail way provided by angular flanges 102 mounted on the upper wall 50 of the shaker frame. Connection is established between hopper 25 and the interior 40 45 of shaker frame 30 by simply sliding this block 100 between flanges 102 until it engages a limiting stop 103, at which time flexible tube 28 is in register with aperture 60. Preferably, the bottom surface of this block is faced with some suitable gasket material, as leather, so that the pressure air developed inside the shaker frame will not escape at this connection.

Shaker frame 30 is alternately moved slowly 50 forwardly (downwardly of the chute), and then quickly retracted, being brought to a sudden stop at the termination of its up or back stroke. This operation is accomplished by the aforementioned cam 19 on shaft 17, said cam 19 bearing against a roller 105 carried at one end of a follower or 55 push rod 106, the latter being slidably mounted in a bearing 107 mounted on the aforementioned cross member 14b of the main frame. In order to maintain roller 105 in proper position with reference to cam 19, push rod 106 is furnished 60 with a laterally projecting pin 109 which works in a longitudinal slot 110 in bearing 107. Push rod 106 projects from bearing 107 through an aperture 111 in cross member 14b and its end acts against the upper end of shaker frame 30. 65 A coil compression spring 112 acting between a shoulder 106a on push rod 106 and a ring 112a confined between bearing 107 and cross member 14b urges push rod 106 in a direction towards cam 19, acting to maintain follower roller 105 against said cam at all times.

The end of the shaker frame is provided in the center with an abutment 114 adapted to engage against an anvil or stop member 115 mounted on frame member 14b; as a simple illustration of suitable means for this purpose, I illustrate a bolt mounted in frame member 14b and arranged with its head adapted to be struck by abutment 114 (see Figs. 1 and 7). The abutment member 114 is mounted on the end of the shaker frame by means of a flange 114a and screws 63. A reinforcing bar 116 is mounted immediately against the inner surface of end wall 31 opposite abutment 114, said member extending, preferably, the full width of the shaker frame. Having been advanced down the incline by cam 19 and push rod 106, the shaker frame is retracted by means of a pair of tension springs 120 connected between frame member 14a and a pair of eyes 121 secured to the end wall 31 of frame 30, these springs 120 passing through apertures 122 in transverse frame member 14b. Another tension spring 124 is preferably connected between the rearward end of the shaker frame and the trough bottom, this latter spring serving to hold the shaker frame down during its vibratory movement.

Cam 19 is formed with a plurality of contiguous cam sections 130, here four in number. Each of these is of progressively increasing radius from the radial shoulder 131 of the preceding cam section to its own radial shoulder 131. Follower roller 105 rides these cam surfaces 130, and under the influence of push rod spring 112, moves inwardly or towards the axis of the cam as it passes over shoulder 131. Thus it will be evident that during a quarter revolution of the cam, follower roller 105 and push rod 106 are slowly advanced, and then, as roller 105 passes over cam shoulder 131, the roller and the push rod are quickly retracted by spring 112.

In the course of the described advancing movement of push rod 106, its end finally engages the end of shaker frame 30, and moves the latter, against springs 120, in a direction down the incline of chute 13. The relations are preferably such that frame 30 is moved, typically, approximately $\frac{1}{8}$ " by this action of push rod 106; however, while this figure is given as typical and preferable, it is to be understood that no limitation is intended. At the moment that follower roller 105 then passes over cam shoulder 131, the push rod is quickly retracted by spring 112, leaving shaker frame 30 to be retracted by springs 120. The latter then pull the shaker frame in an upward direction until abutment 114 strikes against anvil or stop member 115. Springs 120 are sufficiently strong that the shaker frame is retracted very quickly and suddenly, and there is accordingly a substantial impact as the frame strikes stop member 115. As will become apparent hereinafter, the sudden stopping of the frame brought about by bringing it sharply against stop member 115 induces a novel type of separating action.

The operation of the machine is as follows: the material to be separated, as placer gravel containing gold, platinum or other heavy values, is deposited within hopper 25, gate 27 being regulated so that the material flows at a proper rate by way of flexible connection 28 to the interior of shaker frame 30. The material strikes first against wall member 61, and flows from there over steps 65, 66 and 67 in succession, finally being discharged from the shaker frame by way of the discharge opening at the foot of step 67.

The material so discharged is caught by chute 13 and conveyed by the latter out of the machine. Rotation of shaft 17 by means of crank 21 operates bellows 86 and 87 to develop air pressure within flexible tank 95. The pressure air flows from 95 by way of connection 96 to the chamber 45 below shaker frame 30, being distributed by deflector plate 98 to flow more or less uniformly into the several entrance openings in the bottom of the shaker frame. By reason of the dual bellows system pumping into the flexible accumulator for tank 95, the delivery of air into chamber 45 is quite uniform. The pulsations which would occur if it were not for accumulator 95 are smoothed out and a substantially continuous flow of air delivered. This air flows by way of the previously described air passages in shaker frame 30 to be discharged at the head end of the several jagged steps, being discharged across the latter in the general direction of the flow of material thereover. The discharge of air at the head end of each of the steps acts on the material falling onto the corresponding step member to separate out and blow in a forward direction the lighter constituents of the material, and also acts to move the mass of material down the incline. The air discharged below flange 78, at the head end of the section 81 designed for collection of comparatively large particles of gold, of course functions in a similar manner. The air so injected within frame 30 is finally discharged at the lower end of the frame, along with the discharged material.

The mechanical vibratory action of the shaker frame has been previously described; it will be recalled that this action consists of a relatively slow movement down the incline, followed by a quick retractive movement, the latter being sharply terminated by engagement of the frame against an impact member. As previously mentioned, the amplitude of this vibratory action is typically approximately $\frac{1}{8}$ ". Assuming shaft 17 to be rotated at a rate of two revolutions per second or a little less, frame 30 will be driven against stop member 115 at a rate of seven or eight times per second. At such a speed, the machine is very efficient and effective in action. The particles of gold are of course considerably heavier than the gravel or material from which they are to be separated. They therefore, as frame 30 is agitated, settle quickly through the gravel until they engage teeth 70 on step members 65, 66 and 67. These teeth 70, being directed up the incline, hold the particles of gold from sliding down the incline. If the incline were too great, or the downward movement of the shaker should be too rapid, the gold particles would nevertheless, to some extent at least, travel downwardly along these jagged steps. By having the incline of steps 65 not too steep, as for example approximately 4° , and by moving the shaker frame relatively slowly during its downward travel, I am able to prevent practically all of the gold particles which have come into engagement with teeth 70 from traveling down the incline.

On the up stroke of shaker frame 30, the gold particles which have come into engagement with teeth 70 are thrown by said teeth in a direction up the incline. These particles, having become caught by the teeth, are carried along by the latter on the up-stroke of the shaker frame, and when the frame comes to its sudden stop by impacting against stop member 115, the particles of gold which have been carried upwardly by these teeth are projected forcibly in an upward direc-

tion, that is, upwardly of the incline. These particles force their way through the gravel, and finally come to rest at the head end of the particular jagged surface or step which separated them out from the gravel. A peculiar action of the air currents on these gold particles is to be noted. Placer gold is usually principally in the form of more or less flat particles or flakes of various sizes and irregular outlines. The air currents flowing parallel to the jagged steps within the shaker frame, particularly when the cover is in place, are sufficiently strong as to orient these flattish particles of gold parallel to the direction of air flow, and also to cause them to stand on edge, the action being somewhat analogous to the action of wind on the tail of a windmill. This places the gold particles in positions most advantageous for their travel backwardly through the gravel. A number of gold particles are indicated in Fig. 8 as having accumulated at the head end of step 66. These particles will remain in this position until removed from the shaker frame.

Of course, some of the gold particles will not come into engagement with the jagged surface of the first step 65, and will be carried over onto second step 66. And similarly, some of the gold particles may not be caught by second step 66, and will pass on down over section 81 and onto last step 67. The succession of three steps 65, 66 and 67 is, however, adequate to remove a very high percentage of the contained gold, unless the material is flowed through the machine at an undue rate of speed. Any particles of gold too large to be caught and moved by teeth 70 work down in the gravel within section 81 and are caught by pocket 80.

The rate at which the material is run through the machine must of course not be too great, because of the likelihood of carrying out some of the gold. On the other hand, the separating action of the machine is so definite and positive that the material may be handled at good speed. The proper or most efficient speed for any given material may easily be ascertained by experiment. As previously explained, the upwardly directed teeth on the stepped surfaces aid in preventing the particles of gold from going down the incline, and also aid in throwing those particles up the incline on the back stroke of the shaker frame. Of course, even without the teeth, the gold particles would to some extent be moved up the inclined steps, simply by virtue of the characteristic movement given to the shaker frame. Once in engagement with the teeth, however, the separating action becomes positive and rapid. The functional part fulfilled by the air currents must not be minimized. These air currents, discharged at the head end of the jagged steps, act, first, to blow forwardly the lighter constituents of the material, second, to move the mass of gravel down the steps in succession, and third, turn the flakes of gold parallel to the air currents and on edge, so that they may work themselves most readily through the gravel. The incline of the jagged steps is of importance. These steps must not be too steep, as otherwise the particles of gold are carried out. An incline of about 4° affords optimum results, though the machine will operate successfully with the surfaces horizontal. The direction line of reciprocative movement of the shaker frame is not critical, though it is convenient and preferable to move it parallel to the discharge chute. The essential in this respect is

simply that the shaker have a component of movement on the back stroke such that when it is suddenly stopped, the gold particles will be thrown in directions up the jagged inclined surfaces or steps. The speed of movement of the shaker frame is governed by two considerations; first, the speed on the down or forward stroke must not be so great as to cause the gold particles to move down the inclined surfaces when that stroke is stopped, and second, the speed on the up or back stroke must be sufficient that, when the movement of the frame is suddenly arrested, the gold particles will be thrown backwardly through the gravel. In summary, the essential of the required reciprocative movement is that it includes the application of a sudden accelerative force (here specifically the sudden stopping force) to the shaker frame in a direction opposite to the direction in which the impelling surfaces of the teeth face.

I claim:

1. A separator comprising a shaker frame having a series of step-like surfaces at successively lower elevations over which material to be separated may be passed in succession, each of said surfaces being slightly downwardly inclined, and the pitch of the series of steps formed by said surfaces being substantially greater than the inclination of individual surfaces, teeth on said surfaces directed oppositely to the direction of said downward inclination, means supporting said shaker frame for longitudinal reciprocative movement, and means connected with said shaker frame for imparting to it a succession of quick, abruptly arrested movements in the direction in which said teeth are directed.

2. A separator comprising a reciprocative shaker frame, a slightly inclined surface on said frame, an apron depending from the lowermost edge of said surface, a second surface on said frame disposed substantially parallel to and at a lower elevation than said first mentioned surface, the uppermost edge of said second surface being overhung by said apron on said first mentioned surface, and the major portion of said second surface projecting forwardly beyond said apron, teeth on said surfaces directed upwardly of the incline of said surfaces, and an upstanding flange at the uppermost edge of said second mentioned surface, said flange and said apron cooperating to define an air discharge passageway opening at the upper end of said second surface.

3. A separator comprising a shaker frame embodying a nearly horizontal surface having a head end and a foot end, said surface having impelling teeth extending thereacross and directed toward the head end thereof, means supporting said shaker frame for reciprocative movement in a general direction longitudinally of said toothed surface, means for depositing material to be separated onto the head end of said surface, means for discharging air under pressure along a line extending across the head end of said surface, said means directing the air along said surface from the head end toward the foot end thereof, and means for imparting to said shaker frame a succession of quick, abruptly arrested movements in the direction in which said teeth are directed, alternating with relatively slow movements in the reverse direction.

4. A separator comprising a shaker frame embodying a surface having a head end and a foot end and having a slight downward incline from its head end to its foot end, said surface having impelling teeth extending thereacross and di-

rected toward the head end thereof, means supporting said shaker frame for reciprocative movement in a general direction longitudinally of said toothed surface, means for depositing material to be separated onto the head end of said surface, means for discharging air under pressure along a line extending across the head end of said surface, said means directing the air along said surface from the head end toward the foot end thereof, and means for imparting to said shaker frame a succession of quick, abruptly arrested movements in the direction in which said teeth are directed, alternating with relatively slow movements in the reverse direction.

5. A separator comprising a shaker frame embodying a nearly horizontal surface having a head end and a foot end, said surface having impelling teeth extending thereacross and directed toward the head end thereof, means supporting said shaker frame for reciprocative movement in a general direction longitudinally of said toothed surface, means for discharging material to be separated from an elevation spaced above and along a line extending across the head end of said surface so as to fall onto the head end of said surface, means for discharging air under pressure along a line extending across the head end of said surface and just above said surface and just back of the material falling onto said surface, said means directing the air from the head end toward the foot end of said surface, so as to act on the material as it falls onto said surface to blow the lighter constituents thereof toward the foot end of said surface, and to move the mass of material on said surface toward the foot end thereof, and means for reciprocating the shaker frame in a direction generally longitudinal of the toothed surface and for periodically applying to the shaker frame a sudden accelerative force in a direction opposite to the direction of the teeth.

6. A separator comprising a shaker frame embodying a surface having a head end and a foot end and having a slight downward incline from its head end to its foot end, said surface having impelling teeth extending thereacross and directed toward the head end thereof, means supporting said shaker frame for reciprocative movement in a general direction longitudinally of said toothed surface, means for discharging material to be separated from an elevation spaced above and along a line extending across the head end of

said surface so as to fall onto the head end of said surface, means for discharging air under pressure along a line extending across the head end of said surface and just above said surface and just back of the material falling onto said surface, said means directing the air from the head end toward the foot end of said surface, so as to act on the material as it falls onto said surface to blow the lighter constituents thereof toward the foot of said surface, and to move the mass of material on said surface toward the foot end thereof, and means for imparting to said shaker frame a succession of quick, abruptly arrested movements in the direction in which said teeth are directed, alternating with relatively slow movements in the reverse direction.

7. A separator embodying a reciprocative shaker frame having a series of comparatively short, toothed surfaces arranged on said frame at successively lower elevations in step-like formation, and over which material may flow in succession, the teeth of said surfaces extending transversely thereacross and being directed upwardly of the series of steps formed by said surfaces, air passageways adapted to discharge air under pressure in a direction against said teeth from a position immediately above the ends of said surfaces towards which said teeth are directed, and means for imparting to said shaker frame a succession of quick, abruptly arrested movements in the direction in which said teeth are directed.

8. A separator comprising a reciprocative shaker frame, an inclined surface on said frame along which material may flow, an apron depending from the lowermost edge of said surface, in front of which material flowing off the lower end of said inclined surface may fall, a toothed surface on said frame at a lower elevation than said first mentioned surface and arranged with one end portion positioned below and overhung by said depending apron, and with its major area projecting forwardly beyond said apron, the teeth of said surface extending transversely thereacross and pointing in the direction of said apron, the lower edge of said apron and the upper end portion of said toothed surface cooperating to define an air discharge passageway opening across said toothed surface, and means for imparting to said shaker frame a succession of quick, abruptly arrested movements in the direction in which said teeth are directed.
